UNITED STATES PATENT OFFICE.

STEPHEN F. WHITMAN, OF PHILADELPHIA, PENNSYLVANIA.

DESIGN FOR PACKING-BOX.

Specification forming part of Design No. **7,109**, dated January 13, 1874; application filed December 17, 1873.
[Term of Patent 7 years.]

To all whom it may concern:

Be it known that I, STEPHEN F. WHITMAN, of Philadelphia, in the State of Pennsylvania, have invented a Design for a Packing-Box, of which the following is a specification:

The nature of my design is fully represented in the accompanying drawing, to which reference is made.

The box has six sides, two of which, *a a*, are longer than the others, so that the general

shape of the box is an oblong, with pointed ends.

What I claim as my invention is—

The design for a box having two parallel sides and ends beveled from the center to each side, as shown and described.

STEPHEN F. WHITMAN.
